FIG. 1

FIG. 2

FIG. 3

FIG. 4

FIGURE 1 is a front perspective view of an automobile showing our new design;

FIGURE 2 is a front elevation of the automobile; FIGURE 3 is a side elevational view thereof; and

FIGURE 4 is a partial plan view thereof. Portions of the automobile are omitted in FIGURES 3 and 4 for convenience of illustration.

The dominant features of our design reside in the portions shown in solid lines in the drawing. The grill work per se consists of conventional screen.

We claim:

The ornamental design for an automobile, substantially as shown and described.
